Primary Examiner — Alison M Ofstun

(74) Attorney, Agent, or Firm — Tucker Ellis LLP

(57) **CLAIM**

The ornamental design for an hair styler, as shown and described.

DESCRIPTION

FIG. 1 is a perspective view of an hair styler, illustrating our new design;

FIG. 2 is a front view thereof;

FIG. 3 is a left side view thereof;

FIG. 4 is a rear view thereof;

FIG. 5 is a right side view thereof;

FIG. 6 is a top view thereof; and,

FIG. 7 is a bottom view thereof.

(Continued)

The broken lines shown in the drawings illustrate portions of the hair styler that form no part of the claimed design.
